MACHINE FOR STRETCHING AND
COMPRESSING MATERIALSJohn H. V. Finney, Denver, Colo., assignor to The
Gates Rubber Company, Denver, Colo., a cor-
poration of Colorado

Application March 1, 1935, Serial No. 8,889

16 Claims. (Cl. 18—2)

This invention relates to improvements in machines for changing the length of strips of plastic or ductile materials and relates specifically to a machine for stretching or compressing strips of uncured rubber composition.

In the manufacture of automobile tires, the rubber which is to form the tread is first made into strips of the required width and length and these sometimes have a center of considerable thickness and thin edges. When uncured rubber composition is passed through a forming machine, it becomes quite warm while it is worked into the required shape, and it has been found that if the strips are cut into the required length without first compressing the material the sections will not shrink uniformly. It has been found that if the material is compressed sufficiently before it is cut and cooled, the sections will have no further tendency to shrink and will therefore be of substantially uniform length when finished.

It is the object of this invention to produce a machine of simple and substantial construction which can be used for altering the length of a strip of plastic or other material by compressing or stretching the same over its entire width or over a portion of its width only.

This machine, briefly described, comprises two propelling devices so positioned that the strip passes through both, one operates at a different speed than the other so that the material will be either compressed or stretched where it passes from one to the other.

Having thus briefly described the invention and pointed out its objects, the invention will now be described in detail, and for this purpose reference will be had to the accompanying drawing where it has been illustrated in its preferred form and in which

40. Figure 1 is a top plan view of a machine embodying the invention,

Figure 2 is a section taken on line 2—2 of Figure 1 and shows the machine in elevation, portions being broken away to better disclose the construction,

45. Figure 3 is a section taken on line 3—3 of Figure 2, and

Figure 4 is a section taken on line 4—4, Figure 2.

50. In the drawing reference numeral 5 designates the vertical members of frames of the shape of a figure 4, of which there are two; the other members have been designated by reference numerals 6 and 7. The frame can, of course, be constructed in a variety of specifically different ways, and

will therefore not be described with any great particularity.

Secured to the frame members 7 are pairs of bearings 8 and 9 in which are journaled drive shafts 10 and 11. The two pairs of bearings 8 and 9 may be identical and the shafts 11 and 10 may also be identical except as to length. Shaft 11 is provided at one end with a sprocket wheel 12, with which the sprocket chain 13 cooperates to transmit power to the machine. The other ends of shafts 10 and 11 are interconnected by means of gears 14 and 15 of which gear 14 is carried by shaft 10 and in the actual machine has ninety teeth, while gear 15 is connected to shaft 11, and has eighty teeth. It is therefore evident that shaft 10 rotates slower than shaft 11. Secured to each of the shafts are a number of sheaves 16, each of which has a hub 17 which serves as a bearing for an idler 18, (see Figures 3 and 4). In the drawing the machine has been shown as provided with ten sheaves and ten idlers, but a smaller or larger number can be employed. The sheaves and also the idlers are all alike and can be interchanged. The idlers 18 are of greater diameter than the sheaves, as clearly shown in Figures 3 and 4. The sheaves are grooved for the reception of V-belts 19, and the idlers are so spaced that the distance between their adjacent surfaces is slightly greater than the width of the belts.

Pivoted to shaft 10 between the bearings 8 and the collars 20 are arms 21. One end of each arm extends to the right of the sheave and idler assembly on shaft 10, and are connected by a shaft 22 on which are journaled a number of sheaves 23, which lie in the planes of the idlers on shaft 10.

The other ends of arms 21 are provided with weights 24 that can be moved along the arms and may be provided with set screws 25 for holding them in adjusted position.

Belts 19 which encircle the sheaves 16, carried by shaft 11, and corresponding sheaves 23 on shaft 22, are tensioned by the action of the lever arms 21, in a manner quite clear from an inspection of Figure 2. The sheaves on shaft 10 are located in the same planes as the corresponding idlers on shaft 11 and therefore the upper side of belts 19 will rest on the peripheries of the idlers unless separated therefrom.

Lever arms 21a are pivoted at one end to shaft 11 and are connected by a shaft 26 that is located to the left of the sheave and idler assembly carried by shaft 11. Shaft 26 carries a plurality of sheaves 23 like those on shaft 22 and located

in staggered relation to the latter. Belts 19 encircle the sheaves 16 on shaft 10 and sheaves 23 on shaft 26, and are tensioned by the action of the weights 24a.

5 When the machine operates, shaft 11 rotates faster than shaft 10, and belts 19, driven from the sheaves carried on shaft 11, travel faster than those driven from the sheaves carried by shaft 10.

10 Let us now assume that a strip of raw rubber composition 27 is fed into the space between the peripheries of the idlers 18 on shaft 10 and the belts 19 that are driven from shaft 11 and that the parts are rotated in the direction of the 15 arrows in Figure 2. The strip 27 will be carried along by belts 19 and will pass from the upper assembly into the space between the peripheries of the idlers on shaft 11 and the belts driven from shaft 10, but as the belts driven from shaft 10 travel slower than those driven from shaft 11, the material of strip 27 will be compressed in the 20 space between the points where the belts 19 are tangent to the idlers on the two shafts 10 and 11. If the gears 14 and 15 are interchanged, the material will be subjected to a stretching operation.

25 If a portion of the width of the strip only is to be stretched or compressed, some of the belts may be removed.

30 In the instant case, the strip 27 has a center portion 28 of considerable thickness compared to the sides 29, and three belts are sufficient as it is not necessary to alter the lengths of the sides 29, but where a strip of uniform thickness is treated, the number of belts depends on its width.

35 Although the machine illustrated is designed with special reference for use with unvulcanized rubber composition, the principle involved can be employed for changing the length of other materials.

40 The compression or stretching is a continuous process and is uniform and fast.

45 In the drawing, the sheaves 16 have been shown of the same diameter and the shafts 10 and 11 operated at different speeds, but it is obvious that the same results can be obtained by rotating the shafts at the same speed and using sheaves of different diameters.

50 Instead of the gears 14 and 15 shown, any suitable variable speed mechanism can be employed so as to permit the rate of speed to be readily altered to obtain the best results.

55 Instead of weights 24, springs or other equivalent means can be used to provide the necessary tension in the belts.

60 In the specification and on the drawing, the belts 19 have been so located that they lie in the plane of the idlers on the other drive shaft, but this is not an essential feature, but is desirable where soft and pliable material is operated on.

65 In the preferred form, which has been illustrated, the sheaves on the drive shafts and the corresponding sheaves on the idler shafts are so positioned that a tangent common to two cooperating sheaves will intersect the corresponding idler on the other drive shaft but the extent of this intersection can be varied until the chord reaches its minimum length and becomes a tangent and in some instances it may be possible to obtain satisfactory results with thick 70 strips where the belts do not normally contact with the idlers.

75 Attention is called to the fact that the belts are substantially non-extensible and that therefore each point along their lengths travel at the same speed as distinguished from elastic belts

that cooperate with spaced driving pulleys operating at different peripheral speeds. In this device, each set of belts are driven from a single drive shaft.

Having described the invention, what is claimed 8 as new is:

1. A machine for changing the length of a strip of plastic material comprising, in combination, two parallel spaced drive shafts, means for interconnecting the shafts to obtain a constant 10 speed ratio, a plurality of sheaves non-rotatably carried by each shaft, and spaced along the axis thereof, an idler located adjacent each sheave and mounted for free rotation relative thereto, the sheaves and the idlers on one shaft being in 15 staggered relation relative to those on the other shaft, an idler-carrying shaft mounted in parallel relation with each drive shaft, idler sheaves mounted for rotation on the idler shafts, endless belts encircling the sheaves of each drive shaft 20 and corresponding idler sheaves on the cooperating idler shaft, the sheaves being so located that a tangent common to a sheave on a drive shaft and a corresponding idler sheave will intersect the circumference of a corresponding idler 25 on the other drive shaft, and means for driving the two sets of endless belts at different lineal speeds when the machine operates.

2. A machine for changing the length of a strip 30 of plastic material comprising, in combination, two parallel spaced drive shafts, means for interconnecting the shafts to obtain a constant speed ratio, a plurality of sheaves non-rotatably carried by each shaft and spaced along the axis thereof, an idler located adjacent each sheave 35 and mounted for free rotation relative thereto, the sheaves and the idlers on one shaft being in staggered relation relative to those on the other shaft, an idler-carrying shaft mounted in parallel relation with each drive shaft, idler sheaves 40 mounted for rotation on the idler shafts, endless belts encircling the sheaves of each drive shaft, and corresponding idler sheaves on the cooperating idler shaft, the sheaves being so located that a tangent common to a sheave on a drive shaft 45 and a corresponding idler sheave will intersect the circumference of a corresponding idler on the other drive shaft, means for driving the two sets of endless belts at different lineal speeds when the machine operates, and means for yielding 50ingly maintaining a substantially constant tension in the two groups of belts.

3. A machine for changing the length of a strip of plastic material comprising, in combination, two parallel spaced drive shafts, means for interconnecting the shafts to obtain a constant 55 speed ratio, a plurality of sheaves non-rotatably carried by each shaft and spaced along the axis thereof, an idler located adjacent each sheave and mounted for free rotation relative thereto, 60 the sheaves and the idlers on one shaft being in staggered relation relative to those on the other shaft, an idler-carrying shaft mounted in parallel relation with each drive shaft, idler sheaves mounted for rotation on the idler shafts, endless 65 belts encircling the sheaves of each drive shaft, and corresponding idler sheaves on the cooperating idler shaft, the sheaves being so located that a tangent common to a sheave on a drive shaft and a corresponding idler sheave will intersect 70 the circumference of a corresponding idler on the other drive shaft, means for driving the two sets of endless belts at different lineal speeds when the machine operates, the idler sheave shafts being mounted for movement towards and 75

away from their cooperating drive shaft, and yielding means for producing a force tending to move them away from their cooperating drive shaft whereby the cooperating set of belts will be maintained under tension.

5 4. A machine for changing the length of a strip
of plastic material comprising, in combination,
two parallel spaced drive shafts, means for in-
terconnecting the shafts to obtain a constant
10 speed ratio, a plurality of sheaves non-rotatably
carried by each shaft and spaced along the axis
thereof, an idler located adjacent each sheave and
mounted for free rotation relative thereto, the
sheaves and the idlers on one shaft being in
15 staggered relation relative to those on the other
shaft, an idler-carrying shaft mounted in paral-
lel relation with each drive shaft, idler sheaves
mounted for rotation on the idler shafts, endless
belts encircling the sheaves of each drive shaft,
20 and corresponding idler sheaves on the cooper-
ating idler shaft, the sheaves being so located
that a tangent common to a sheave on a drive
shaft and a corresponding idler sheave will in-
tersect the circumference of a corresponding idler
25 on the other drive shaft, means for driving the
two sets of endless belts at different lineal speeds
when the machine operates, the idler sheave
shafts being mounted for movement toward and
away from their cooperating drive shaft, and
30 yielding gravity-responsive means for produc-
ing a force tending to move them away from
their cooperating drive shaft whereby the co-
operating set of belts will be maintained under
tension.

35 5. A machine for changing the length of a strip of plastic material comprising in combination a supporting frame, two spaced parallel drive shafts rotatably carried by the frame, means for maintaining a fixed ratio of rotation between the
40 shafts, a pair of levers pivotally connected to the frame adjacent each drive shaft, an idler-carrying shaft supported by each pair of levers, the idler shafts being so positioned relative to the drive shafts that a line joining an idler shaft and the drive shaft that cooperates with it will be intersected by a perpendicular from it to the other drive shaft, a plurality of sheaves non-rotatably secured to each drive shaft and spaced apart thereon, an idler mounted for free rotation adjacent each sheave, the idlers being of longer diameter than the sheaves, the idlers and sheaves on the two drive shafts being arranged in staggered relation, a plurality of idler sheaves on each idler shaft, endless belts encircling the
50 sheaves on each drive shaft and corresponding idler sheaves, means for producing a yielding force on each pair of levers tending to turn them in a direction to tighten the belts, and means for imparting to the two sets of belts different lineal
55 speeds.

60 6. A machine for changing the length of a strip of plastic material comprising, in combination, two parallel spaced drive shafts, means for interconnecting the shafts to obtain a desired speed 65 ratio, a plurality of sheaves non-rotatably carried by each shaft, and spaced along the axis thereof, an idler located adjacent each sheave and mounted for free rotation relative thereto, an idler-carrying shaft mounted in parallel relation with each 70 drive shaft, idler sheaves mounted for rotation on the idler shafts, endless belts encircling the sheaves of each drive shaft and corresponding idler sheaves on the cooperating idler shaft, the sheaves being so located that a tangent common 75 to a sheave on a drive shaft and a corresponding

idler sheave will intersect the circumference of a corresponding idler on the other drive shaft, and means for driving the two sets of endless belts at different lineal speeds when the machine operates.

7. A machine for changing the length of a strip of plastic material comprising, in combination, two parallel spaced drive shafts, means for interconnecting the shafts to obtain a desired speed ratio, a plurality of sheaves non-rotatably carried by each shaft, and spaced along the axis thereof, an idler located adjacent each sheave and mounted for free rotation relative thereto, the sheaves and the idlers on one shaft being in staggered relation relative to those on the other shaft, an idler-carrying shaft mounted in parallel relation with each drive shaft, idler sheaves mounted for rotation on the idler shafts, endless belts encircling the sheaves of each drive shaft and corresponding idler sheaves on the cooperating idler shaft, and means for driving the two sets of endless belts at different lineal speeds when the machine operates.

8. A machine for changing the length of a strip of plastic material comprising, in combination, two parallel spaced drive shafts, means for interconnecting the shafts to obtain a desired speed ratio, a plurality of sheaves non-rotatably carried by each shaft, and spaced along the axis thereof, an idler located adjacent each sheave and mounted for free rotation relative thereto, an idler-carrying shaft mounted in parallel relation with each drive shaft, idler sheaves mounted for rotation on the idler shafts, endless belts encircling the sheaves of each drive shaft and corresponding idler sheaves on the cooperating idler shaft, and means for driving the two sets of endless belts at different lineal speeds when the machine operates. 25 30 35

9. A machine for changing the length of a strip of plastic material comprising, in combination, two parallel spaced drive shafts, means for interconnecting the shafts to obtain a desired speed ratio, a plurality of sheaves non-rotatably carried by each shaft and spaced along the axis thereof, an idler located adjacent each sheave and mounted for free rotation relative thereto, the sheaves and the idlers on one shaft being in staggered relation relative to those on the other shaft, an idler-carrying shaft mounted in parallel relation with each drive shaft, idler sheaves mounted for rotation on the idler shafts, endless belts encircling the sheaves of each drive shaft, and corresponding idler sheaves on the co-operating idler shaft, means for driving the two sets of endless belts at different lineal speeds when the machine operates, and means for yieldingly maintaining a substantially constant tension in the two groups of belts.

10. A machine for changing the length of a strip of plastic material comprising, in combination, two parallel spaced drive shafts, means for interconnecting the shafts to obtain a desired speed ratio, a plurality of sheaves non-rotatably carried by each shaft and spaced along the axis thereof, an idler located adjacent each sheave and mounted for free rotation relative thereto, an idler-carrying shaft mounted in parallel relation with each drive shaft, idler sheaves mounted for rotation on the idler shafts, endless belts encircling the sheaves of each drive shaft, and corresponding idler sheaves on the cooperating idler shaft, the sheaves being so located that a tangent common to a sheave on a drive shaft and a corresponding idler sheave will intersect the circum-

ference of a corresponding idler on the other drive shaft, means for driving the two sets of endless belts at different lineal speeds when the machine operates, and means for yieldingly maintaining a substantially constant tension in the two groups of belts.

11. A machine for changing the length of a strip of plastic material comprising, in combination, two parallel spaced drive shafts, means for interconnecting the shafts to obtain a desired speed ratio, a plurality of sheaves non-rotatably carried by each shaft and spaced along the axis thereof, an idler located adjacent each sheave and mounted for free rotation relative thereto, an idler-carrying shaft mounted in parallel relation with each drive shaft, idler sheaves mounted for rotation on the idler shafts, endless belts encircling the sheaves of each drive shaft, and corresponding idler sheaves on the cooperating idler shaft, means for driving the two sets of endless belts at different lineal speeds when the machine operates, and means for yieldingly maintaining a substantially constant tension in the two groups of belts.

12. A machine for changing the length of a strip of plastic material comprising in combination, two strip propelling devices, operating to move the strip in the same direction, each device operating at a different speed, each device comprising a plurality of substantially non-extensible belts for engaging one side of the strip, and a means for holding the strip in contact with the moving belts.

13. A machine for effecting a uniform change in the length of each unit length of a moving strip of plastic material, comprising two strip feeding devices, each of which has as one element thereof, a plurality of endless, substantially non-extensible belts for contacting one side 40 of the strip, movable means for forcing the strip against the belts of each device, the belts of the

two devices operating at different speeds, whereby by the strip, as it is transferred from one device to the other, is subjected to a change in length.

14. A machine for changing the length of a strip of plastic material, comprising two strip feeding devices, each of which has, as an element, a plurality of endless, substantially non-extensible belts, the belts on each device encircling pulleys on spaced parallel shafts, means associated with the belts of each device for urging the strip against the outside of the belts, and means for moving the belts in the same direction but at different speeds, whereby that portion of the strip lying between the two propelling devices will be changed in length. 15

15. A machine for changing the length of a strip of plastic material comprising in combination, two strip propelling devices, operating to move the strip in the same direction, each device operating at a different speed, each device comprising a substantially non-extensible belt for engaging a side of the strip, the belts each engaging a different side of the strip, and means positioned on opposite sides of the strip for forcing the other side thereof into contact with one 25 of the belts.

16. A machine for changing the length of a strip of plastic material comprising in combination, two strip propelling devices formed from two assemblies, each of which comprises two spaced 30 parallel shafts, one of which is a drive shaft, a drive pulley on the drive shaft, an idler pulley on the other shaft and a belt encircling the two pulleys, means for driving the belts at different lineal speeds, the shafts of one assembly being 35 staggered with respect to those of the other assembly, but parallel therewith, and means on each assembly for urging longitudinally spaced parts of a plastic strip, positioned between the assemblies, against the belt of the other assembly. 40
